UNITED STATES PATENT OFFICE

162,274

FENCE POST TOP ORNAMENT

Bernard Youngworth, Baltimore, Md.

Application March 7, 1950, Serial No. 8,384

Term of patent 14 years

(Cl. D28—1)

To all whom it may concern:

Be it known that I, Bernard Youngworth, a citizen of the United States, residing at Baltimore city, State of Maryland, have invented a new, original, and ornamental Design for a Fence Post Top Ornament, of which the following is a specification, reference being had to the accompanying drawings, forming a part hereof.

I claim:

The ornamental design for a fence post top ornament, as shown.

BERNARD YOUNGWORTH.
